[57] CLAIM

The ornamental design for a combined breast shield and milk collector, as shown and described.

DESCRIPTION

FIG. 1 is a front elevational view of a combined breast shield and milk collector showing my new design; FIG. 2 is a side elevational view, the opposite side being a mirror image thereof;

FIG. 3 is a top plan view;

FIG. 4 is a bottom plan view;

FIG. 5 is a rear elevational view; and

FIG. 6 is a sectional view taken along line 6—6 of FIG. 5.
